RECEIVING CIRCUIT

John B. Moore, Riverhead, N. Y., assignor to
Radio Corporation of America, a corporation
of Delaware

Application November 23, 1933, Serial No. 699,318

8 Claims. (Cl. 250—20)

This invention relates to multiple detection radio receiving circuits and is particularly concerned with the intermediate frequency stages of such receivers.

5 Due to the fact that radio receivers now in general use have a fixed frequency band width, it is necessary in the reception of various types of service to have as many different types of receivers as there are different services. As an illustration, in the reception of telephone, program or facsimile service it has been found that a receiver having a rather wide frequency band width is required, whereas, at other times, in order to receive telegraph signals and to prevent interference from adjacent channels it is necessary to have a much narrower frequency band width. In the use of short waves particularly, where varying channel spacings are involved, it is usual to have a plurality of receivers to handle the 20 different types of services.

Heretofore in the use of these receivers, particularly those of the multiple detection type, the construction of the apparatus has not been such as to lend itself readily for use with different services, especially so since there is required in this type of apparatus a change of the band width in the intermediate frequency amplifier system for each type of service. To accomplish such a change has involved in most cases retuning of 25 the coupled circuits, a change which is rather difficult for inexperienced operators who have a limited knowledge of the radio art. It has further been found that if several circuits are used, the process of changing over from one band width 30 to another in order to obtain a desired selectivity is rather a slow and tedious proposition even for an experienced operator.

It is an object of the present invention to overcome these disadvantages by providing greater 40 flexibility in radio receiving systems so as to enable quick and efficient change-over in a receiver from one band width to another.

Another object is to provide such a change-over system wherein the switching from one band width to another is done in a quick and efficient manner and by the use of simple switching mechanism.

Briefly, the present invention contemplates the use in a multiple detection receiver of an interchangeable filter arrangement comprising a plurality of filter units in the second intermediate frequency amplification stage for obtaining instant change-over of the band width in the receiver. To accomplish this, there is employed 55 simple switching mechanism for switching from

one filter unit to another. Thus, there is obtained an arrangement which permits instant changing over to be made in a very simple way by even the most inexperienced operators.

One advantage of the present invention has been found to reside in the far greater degree of selectivity which can be obtained than from an equal number of transformer coupled stages of amplification.

In the accompanying drawings, Figure 1 shows, 10 diagrammatically, a multiple detection receiver embodying the features of the present invention, and Figure 2 illustrates, graphically, the band widths available from the receiving system depicted.

Referring to Figure 1 in more detail, there is shown a well known type of triple detection receiver comprising a plurality of radio frequency stages 1 and 2 coupled to a detector 3 which, in turn, is arranged to produce, in combination with an oscillator 4, a beat frequency which is supplied to the first intermediate frequency amplifier stage 5. A filter unit 22 in the output of amplifier stage 5 serves to provide part of the desired degree of selectivity required. From this filter unit, the signals at the beat frequency are fed to intermediate frequency detector 7 where they combine with oscillations from an intermediate frequency oscillator 6 which serves to produce in the output of detector 7 a lower frequency beat note which is fed to the first stage 8 of the second intermediate frequency circuit and then through a desired intermediate frequency filter unit of the interchangeable filter arrangement and other stages of the second intermediate frequency amplifier to the final detector 9 from which the audio frequency components are passed 30 to any suitable utilization circuit 10.

In the particular embodiment shown, the tuning is accomplished in the radio frequency amplifier stages 1 and 2, the tunings of the individual intermediate frequency filters 11 and 12 of the interchangeable filter arrangement being fixed in their design once and for all. These interchangeable filters have any suitable band widths and 45 are provided with a single pole, double throw switch at the input and output ends of the filter for enabling proper switching of the amplifier from one filter to the other. As indicated in the drawings, the operation of the switch by means 50 of a unicontrol arrangement herein designed by the dotted line 21 connects the anode lead 14 of the input tube 8 in the second intermediate frequency amplifier to either one of the filters and also switches simultaneously the control grid 15 55

5 of the following tube 19 to the corresponding filter. These filters may be any of the well known types which may be used to determine the overall band width of the receiving equipment, and since the design of the filter, per se, forms no part of the present invention it will not be described herein.

10 By the use of switching mechanism 13 one is easily enabled to quickly change the band width 10 of the receiver merely by interchanging the filter units and thus to provide a quicker and more advantageous scheme than that obtained by the use of tuned transformers between the stages.

15 Figure 2 illustrates, by way of example only, 15 suitable different band widths which may be obtained by means of the present invention. In this figure, graph A represents a band width of twenty kilocycles which is the band width passed by the first intermediate frequency filter, and graph B 20 illustrates a band width of ten kilocycles which one of the filters 12 is designed to pass, let us say, for program service. Graph C, however, shows a three kilocycle band width which filter 11 may be designed to pass, for another type of service.

25 The present invention, it is to be understood, is not limited to the precise arrangements shown since numerous modifications may be made by those skilled in the art without departing from the spirit and scope of the invention. For example, instead of the two filter circuits shown, 30 any two channels having different band width characteristics may be employed.

I claim:

1. The combination in a multiple detection receiving circuit having a high frequency amplification system and at least one intermediate frequency amplification system operatively connected thereto, of an interchangeable filter arrangement selectively connectable in circuit with 35 said intermediate frequency amplification system, said filter arrangement comprising a plurality of filters having different frequency ranges mutually inclusive of a given mid-band frequency and switching mechanism for operatively associating 40 said intermediate amplification system with any 45 one of said filters.

2. A super-heterodyne receiving circuit comprising a radio frequency amplification system, a first intermediate frequency amplification system 50 including a band-pass filter, and a second intermediate frequency amplification system, said last system comprising a first electron discharge tube having an output circuit and a second electron discharge tube having an input circuit, a plurality 55 of filters having substantially identical mid-band frequency characteristics but differing one from another as do their respective frequency ranges, said filters being interposed between the output of said first tube and the input of said second tube, and switching mechanism in said output and input circuits for connecting said input and output circuits with one of said filters at a time.

3. A receiver as defined in claim 2 characterized 60 in this, that said switching mechanism comprises 65 two unicontrol single pole double-throw switches.

4. In combination, an electron discharge device having an input circuit and another electron discharge device having an output circuit, two band-pass filter units between said input and output circuits, one of said band-pass units having a 5 pass range substantially centrally disposed within the pass range of said other filter unit, and means for selectively connecting one only of said band-pass units simultaneously to said input and output circuits.

5. A super-heterodyne receiving circuit comprising a radio frequency amplification system, a first intermediate frequency amplification system including a band-pass filter having a band-pass 10 range of at least 20 kilocycles, and a second intermediate frequency amplification system, said last system comprising a first electron discharge tube having an output circuit and a second electron discharge tube having an input circuit, a plurality of band-pass filters between the output of said first tube and the input of said second tube, one of said filters having a band-pass range of at least 15 10 kilocycles and the other of said filters having a band-pass range of at least 3 kilocycles within said 10 kilocycle range, and switching 20 mechanism in said output and input circuits for connecting said input and output circuits with one of said filters at a time.

6. In a super-heterodyne receiving circuit, an intermediate frequency amplifying system comprising an electron discharge device having an input circuit and another electron discharge device having an output circuit, two band-pass filter units between said input and output circuits, 30 said units having the same mid-band frequency but different band widths, and switching mechanism in said input and output circuits for operatively connecting said electron discharge devices simultaneously with one of said two filter units, but not with both.

7. In a superheterodyne receiving circuit, a radio frequency amplification system, a first intermediate frequency amplification network connected to said system and including a band-pass filter, and a second intermediate frequency amplification network adapted to be fed with energy from said filter, the last said network having interposed between two of its stages a plurality of selectively connectable band-pass filters 45 each of progressively more and more restricted frequency range than the range of the first said band-pass filter, and each having substantially the same mid-band frequency as that of the others.

8. In a receiving system, an energy collecting circuit, an output circuit, a pair of filters each having different pass widths but adapted to pass the same mean frequency, and switching means associated with said energy collecting circuit and said output circuit for selectively causing the transfer of energy from said energy collecting circuit to said output circuit through either one only of said filters during any particular period of time.

JOHN B. MOORE.
